[57] CLAIM

The ornamental design for a scraper handle, as shown and described.

DESCRIPTION

FIG. 1 is a perspective view of a scraper handle showing my new design;

FIG. 2 is top plan view thereof;

FIG. 3 is a bottom plan view thereof;

FIG. 4 is a left-hand side elevation view thereof;

FIG. 5 is a right-hand side elevation view thereof;

FIG. 6 is a rear elevational view thereof; and,

FIG. 7 is front elevation view thereof.

The broken line showing the razor is for illustrative purposes only and forms no part of the claimed design.

FIG. 1

FIG. 7

FIG. 6

FIG. 2
